UNITED STATES PATENT OFFICE.

GEORGE L. BROWN, OF PLANT CITY, FLORIDA.

FOUNTAIN TOOTH-BRUSH.

1,260,139.

Specification of Letters Patent. Patented Mar. 19, 1918.

Application filed April 28, 1917. Serial No. 165,206.

To all whom it may concern:

Be it known that I, GEORGE L. BROWN, a citizen of the United States, residing at Plant City, in the county of Hillsborough and State of Florida, have invented new and useful Improvements in Fountain Tooth-Brushes, of which the following is a specification.

This invention relates to fountain tooth brushes and it consists in the novel features hereinafter described and claimed.

An object of the invention is to provide a brush of the character indicated which is of sanitary nature, convenient to manipulate and economical to manufacture and maintain.

With these and other objects in view the tooth brush comprises a reservoir which may be used as a handle and which may retain a quantity of paste. This reservoir is provided at one end with a vent and a resilient frame is located at that end of the reservoir which is provided with the vent. A spring pressed valve is mounted upon the reservoir and normally closes the vent thereof. A plunger is mounted for movement within the reservoir and is slidably mounted upon a rod, there being means for moving the plunger in one direction with the movement of the rod but permitting the plunger to remain at a state of rest when the rod moves in an opposite direction. A conically coiled spring is operatively connected with the said rod and is adapted to normally hold the same in a retracted position in the reservoir, a detachable hood is applied to the reservoir and houses the said spring. A brush body is adapted to be applied to the said resilient frame and carries bristles which are adapted to receive upon their ends the paste from the reservoir when the same is expelled through the vent.

In the accompanying drawing:

Figure 1 is a longitudinal sectional view of the brush;

Fig. 2 is a detail fragmentary sectional view of the intermediate portion thereof;

Fig. 3 is a transverse sectional view of the brush cut on the line 3—3 of Fig. 2;

Fig. 4 is a perspective view of a clutch member used in the brush;

Fig. 5 is a plan view of the frame which is mounted upon the reservoir of the brush;

Fig. 6 is a transverse sectional view of the brush cut on the line 6—6 of Fig. 1;

Fig. 7 is a similar view cut on the line 7—7 of Fig. 1;

Fig. 8 is a perspective view of a container which may hold the paste which is supplied to the reservoir.

60

The fountain brush comprises a reservoir 1 adapted to receive a paste or other suitable emulsion and which carries at one end a resilient frame 2. The said frame 2 is provided at its side edges with upstanding flanges 3 which in turn are provided at their upper edges and at points between their ends with inwardly disposed tongues 4. An inwardly disposed tongue 5 (best shown in Fig. 1) is provided at the end of the frame 70 2. The frame 2 is adapted to support a brush which consists of a back 6 having grooves 7 and 8 adapted to receive the tongues 4 and 5 respectively. The said brush is further provided with bristles 9, 75 the upper or free ends of which lie in a compound curved line as best shown in Fig. 1. The grooves 7 are located at the opposite side edges of the back 6 and the groove 8 is located at the end thereof. When the 80 brush is inserted in position upon the frame 2, the tongue 5 is inserted in the groove 8 and the back 6 is pressed down so that the said frame is sprung laterally and the tongues 4 may enter in the groove 7. Thus 85 the brush is securely held in position upon the frame 2 but may be readily detached therefrom by reversing the operation just described. When the brush is in position upon the frame the flanges 3 close the space 90 between the edges of the back 6 and the body of the frame 2 thus preventing foreign substance from accumulating between the back 6 of the brush and the body portion of the frame 2.

95

That end of the reservoir 1 which is adjacent the frame 2 is provided with a vent 10 and a valve 11 is pivoted to the reservoir 1 adjacent the said vent. A spring 12 is fixed at one end to the body of the frame 1 100 and bears at its other end against the edge of the valve 11 and is under tension with a tendency to normally hold the valve 11 in a closed position over the vent 10. A tube 13 is adapted to be slipped over that end 105 of the reservoir 1 which is adjacent the frame 2 and the said tube incloses the said frame and the brush.

Absorbent material 14 as for instance cotton is located in one end of the tube 13 and 110

may be treated with a medicament or sterilizing agent and is held in position by a perforated plate 15 located within the tube 13. When the brush is inclosed within the tube 13 it is subjected to the fumes from the medicament or sterilizing agent and thus the bristles of the brush are maintained in a sanitary condition when the device is not in use.

10 A plunger 16 is slidably mounted in the reservoir 1 and a rod 17 passes through the same and may slide therein. The plunger 16 is provided with a packing 16' of rubber or other suitable material which bears 15 against the rod 17 and the inner surface of the reservoir 1 and prevents the paste from passing behind the plunger. The rod 17 is provided at its inner end with an enlarged head 18 and in the vicinity of its other end 20 with a stop 19 which is adapted to encounter the end of the reservoir 1 as shown in Fig. 1 of the drawing. A hood 20 is attached to the outer end of the rod 17 and is provided with a reduced inner portion 21 adapted to 25 be slipped over the humps 22 provided upon the reservoir 1 whereby the said hood is maintained in position upon the reservoir but may have slight longitudinal movement with relation to the same. A cone shaped 30 spiral spring 23 is interposed between the end of the reservoir 1 and the inner surface of the hood 20 and is under tension with a tendency to normally maintain the stop 19 of the rod 17 in engagement with the end 35 of the reservoir 1. A clutch member 24 is carried by the plunger 16 and the said member is provided with tongues 25 which are adapted to engage the inner surface of the reservoir 1. The said clutch member is further provided with tongues 26 adapted to 40 engage the rod 17 as best indicated in Fig. 2 of the drawing. The said tongues 25 and 26 are disposed in the said general direction with relation to the adjacent surface of the 45 plunger 16 but they are disposed at angles with relation to each other so that the plunger 16 is forced to move with the rod 17 when the said rod is moved in one direction but the rod 17 may move in an opposite direction without moving the plunger 16. This is due to the fact that when the rod 17 is moved in the direction last indicated the tongues 25 frictionally engage the sides of the reservoir 1 and hold the plunger 16 50 agains movement. A block 27 is carried by the plunger 16 and is attached thereto by means of bolts or other securing devices 28 and serve as means for holding the clutch member 24 in position with relation to the 55 plunger.

In Fig. 8 of the drawing is shown a con-

tainer 29 in perspective which retains the paste or other lotion which is adapted to be filled in the reservoir 1.

The material from the container 29 is placed in the reservoir 1 as shown in Fig. 1 after the plunger 16 has been removed therefrom and the hood 20 detached from the end of the said reservoir. The said plunger 16 is then replaced in the reservoir 1 and the reduced end portion 21 of the hood 20 is engaged over the hump 22 of the said reservoir. As the paste or lotion is used the hood 20 is forced in an inward direction toward the end of the reservoir 1 where- 75 by the plunger 16 is moved toward the vent 10 and the paste or lotion is forced through the said vent and over the curved line de- 80 scribed by the ends of the bristles 9 of the brush. As the lotion moves through the 85 vent 10 it forces the valve 11 to an open position but as soon as the movement of the lotion or paste ceases the tension of the spring 12 comes into play whereby the valve 11 is moved to a closed position over the vent 90 10 and the stream of lotion is cut thus leav- 95 ing a portion thereof upon the ends of the bristles 9 of the brush. The brush may then be used upon the teeth in an ordinary manner and after the cleaning operation has 100 been performed, the tube 13 may be placed in position upon the reservoir 1 whereby the frame 2 and the brush are inclosed and the bristles of the brush are subjected to the sanitary action hereinbefore described. 105

From the foregoing description taken in conjunction with the accompanying drawing, it will be seen that a fountain tooth brush of simple and durable structure is provided and that the same includes economic 100 and sanitary features, and may also be easily and readily used for cleaning the teeth.

Having described the invention what is claimed is:—

A brush of the character stated comprising a reservoir having a vent, a brush body mounted on the reservoir adjacent the vent, a rod slidably mounted in the reservoir, a plunger slidably mounted on the rod and slidably in the reservoir and including a packing of relatively soft material which bears at one edge against the rod and at its other edge against the inner surface of the reservoir, a clutch device engageable with the rod and reservoir to hold the plunger at adjusted position, a block located adjacent the clutch device and securing devices passing transversely through the plunger, the clutch device and the block. 110

In testimony whereof I affix my signature. 115

GEORGE L. BROWN.
